UNITED STATES PATENT OFFICE

DAVID H. McFALLS, OF WHITE PLAINS, NEW YORK

GAME

1,174,171.

Specification of Letters Patent. Patented Mar. 7, 1916.

Application filed March 22, 1915. Serial No. 16,051

To all whom it may concern:

Be it known that I, DAVID H. MCFALES, a citizen of the United States of America, residing at the city of White Plains, in the county of Westchester and State of New York, have invented certain new and useful Improvements in Games, of which the following is a specification.

10 My invention relates to games, and the object of my invention is to provide a bowling game adapted to be played in a parlor, with means for throwing a ball and directing it as desired; together with such other elements and combinations as are hereinafter more particularly set forth and claimed. I accomplish these objects by means of the mechanism illustrated in the accompanying drawing, in which:

Figure 1 is a plan. Fig. 2 is a longitudinal section. Fig. 3 is an elevation of the catapult or throwing device. Fig. 4 is a side elevation of the catapult or throwing device. Fig. 5 is a sectional view through the plate O, showing the manner of the attachment of the clip basket to the handle.

Similar letters refer to similar parts throughout the several views.

The table, A, is of oblong formation and may be fourteen inches wide and six feet long; although I do not limit myself to the size, and is constructed like a bowling alley, provided at one end with a box or receptacle, B, into which the pins, C, may be caught when they are knocked down by the ball, D. For the purpose of returning the ball after it has been shot toward the pins and has

entered the receptacle, B, I place the return runway, E, communicating with the receptacle and leading to and the end of the tail.

40 tacle and leading toward the end of the table occupied by the "shooter." For the purpose of shooting or throwing the ball, D. I. secure

of shooting or throwing the ball, D, I secure a bracket, F, at one end of the table, which bracket may be constructed of wire bent to form two parallel uprights, *f*, *f*, and a cor-

45. form two parallel uprights, ℓ , ℓ , and a connecting portion, g , at right angles to the uprights, and having at the upper corners suitable eyelets, G , G , with corresponding eyelets, g , g , in the connecting portion, g , so that the uprights, ℓ , ℓ , may be secured to the connecting portion, g , by bolts, b , b , passing through the eyelets, G , G , and g , g , respectively.

able eyelets, G, G, with corresponding eyelets, H, H, near the bottom of each of the uprights, f, f. At midway between the uprights, f, f, and the connecting piece, g, or

50 rights, *f*, *f*, and the connecting piece, *g*, on the table, I mount a clip basket, *J*, holding the ball, *D*. The clip basket, *J*, is provided with a plate, *O*, which is connected to the eye-

I do not limit my invention, the catapult, to a bowling game. The game described herein is simply an illustration of the use to which my invention may be put. 90

What I claim as my invention and desire to secure by Letters Patent is: 95

1. A catapult adapted to be used in a parlor game, comprising a bracket made up of two uprights separated from each other, their upper ends joined by a strip with eyelets formed at the juncture of the uprights and said strip, the uprights provided with eyelets near the table; a table to which one end of said uprights are secured; a plate mounted about midway between the sides and ends of said bracket; a series of springs secured at one end to said eyelets and at the

other end to said plate; a clip basket formed on said plate; and a handle for moving said clip basket at any desired angle.

2. A catapult adapted to be used in a par-
5 lor game, comprising a bracket; a table to
which said bracket is attached; a plate
mounted about midway between the sides of
the bracket; a series of springs, each secured
at one end to the plate and at the other to

the bracket; a clip basket and a handle, to 10
which the clip basket is attached for moving
said clip basket; as desired.

In testimony whereof I have affixed my
signature in presence of two witnesses.

DAVID H. McFALLS.
